UNITED STATES PATENT OFFICE.

JOHN H. REOHR, OF YONKERS, NEW YORK, ASSIGNOR, BY MESNE ASSIGNMENTS, TO THE MAGAZINE AND BOOK COMPANY OF NEW YORK, A CORPORATION.

MEANS FOR COÖPERATIVE ADVERTISING.

No. 853,473.

Specification of Letters Patent.

Patented May 14, 1907.

Application filed January 23, 1905. Serial No. 242,256.

To all whom it may concern:

Be it known that I, JOHN H. REOHR, a citizen of the United States, and a resident of the city of Yonkers, county of Westchester, 5 State of New York, have invented certain new and useful Improvements in Means for Coöperative Advertising.

My invention relates to means for practicing a novel method of co-operative advertising.

The object of my invention is to provide means whereby, through an intermediary, the producers of various commodities and the publishers of various periodicals may co-operate in advertising, and thus each greatly increase the scope of its publicity, and also decrease the relative cost to it thereof, while, concurrently, both advertise the intermediary, which, in turn, also advertises them.

20 A further object of my invention is to provide means whereby the amount of advertising may be proportioned to the returns therefrom, and the cost thereof limited to correspond to its productive results.

25 A further object of my invention is to provide means whereby a producer or publisher can quickly and accurately ascertain the volume of sales of his articles in a given locality, the results of his advertising, whether productive or otherwise, and the fields where such advertising will be either unnecessary or advantageous.

30 A further object of my invention is to increase the demand for the standard goods and publications issued by the respective members of the co-operative system, and to prevent unfair competition by minimizing their fraudulent imitation.

35 I accomplish these objects by the use of my invention as hereinafter described and claimed, reference being had to the accompanying drawings, which form a part of this specification.

40 The device consists of a coupon leaflet comprising a premium list of publications, a purchasing list of commodities and their producers, a detachable and redeemable coupon, with inter-referring letters and numbers upon the various parts.

45 In the drawings, Figure 1 shows the front page with the coupon and a portion of the premium list. Fig. 2 shows the back page, with a part of the purchasing list.

The premium list consists of the names of a selected series of publications of publishers 55 practicing my system, one only being chosen from each class, or field of subject, religious, financial, sporting, etc. Opposite the name of each is a number indicating the number of whole coupons necessary to be secured by a 60 purchaser of the articles contained in the purchasing list to procure a paid-up yearly subscription to that particular publication.

The purchasing list comprises a list of articles of general consumption, issued by their 65 respective producers who, in turn, practice my system, and after each, the name of the producer of that article. Each article is one of a distinct class of merchandise so that no two producers are brought into competition. 70 Opposite the name of each brand or producer is an identification number which is always used to represent that particular producer. If a single producer advertises more than one article, each article is lettered consecutively, the identification number, together with the brand letter, always representing that particular article of that particular producer. The coupon contains a statement of its face value, which value is, in 75 my system, absolutely fixed as its redeemable value in cash equivalency. It also contains the address of the intermediary, the identification number and brand letter, together with a checking number, the importance of which will more clearly appear hereafter.

In practice the device is used as follows: The intermediary secures the co-operation of a number of publishers of periodicals or 80 printed publications, one from each class, and a number of non-competitive producers, one only for each kind of article on the list. The names of these publications are printed upon the premium list of the leaflet, and the 85 names of the producers, together with the articles produced by each, upon the purchasing list. Each producer agrees to inclose a coupon leaflet in each package of the article advertised by him thereon, and each publisher contracts to give space for a reproduction of a fac-simile of the leaflet. The consumer detaches the coupon found in various staple articles purchased by him, forwards the proper number of them to the intermediary, and is credited by it with a paid-up 90 95 100 105

subscription to the publication selected by him from the list, the intermediary company paying cash to the publisher for such subscription so credited. The intermediary company then sorts the coupons by means of the identification numbers, and forwards them to the issuing producers, who redeem them at their face value in cash to the intermediary. By the use of the coupon leaflet, in this way, each publisher and each producer advertises himself and all the others of both classes, and advertises and is advertised by the intermediary, giving to each one a correspondingly increased amount of advertising at a very low cost. Moreover, by the redemption and identification of the coupons, the cost of advertising is ratably proportioned to the resulting sales, and paid upon that basis solely, a system of guaranty impossible under the systems now in use, non-productive advertising costing the advertiser nothing.

An important feature of this coupon leaflet is the system of inter-referring identification and checking numbers. The coupons attached to the leaflets delivered to any producer bear the identification number assigned solely to him, and if he advertises more than one article, those coupons placed in one article bear one brand-letter, and those inclosed in another article, bear another. In addition each coupon has a checking number, by means of which the producer can trace the package in which it was contained, and which, likewise, serves as a safeguard against counterfeiting of the coupon or of the commodity. The importance of these figures and letters can hardly be overstated. It both enables the intermediary to identify the issuing producer and thus charge him for his advertising proportionately to the resulting sales; and, since in premium advertising, statistics have been compiled showing the proportion of coupons returned, to the total number issued, the producer is enabled to determine where his goods are being sold, making it possible to decide where his advertising is needed and where it is superfluous. In short, it gives the producer a quick and accurate report of the trade-conditions in any given locality to which his goods containing the coupon leaflets are sent.

It is obvious that my means for co-operative advertising may be embodied within a leaflet, or single-sheet, as shown, or may be expanded by a longer list of premiums or vendible commodities, so as to require a number of sheets, without departing from the spirit of my invention. It is also obvious that other modifications of form may be substituted without substantially altering my idea of means and instrumentalities herein described.

Having thus described my invention, what I claim is:

1. Means for co-operative advertising comprising a leaflet, consisting of a list of periodicals, a list of commodities, a list of producers of said commodities, and a coupon, said coupon containing a notice that it is redeemable in payment for subscriptions to the periodicals contained in said list. 70

2. Means for co-operative advertising comprising the combination of a printed leaflet and an attached coupon; said leaflet comprising a classified list of periodicals or similar publications, a list of commodities of different kinds and their respective producers, said coupon containing a promise of the issuing party to redeem said coupon and directions 80 to the holder for securing such redemption.

3. Means for co-operative advertising comprising the combination with a printed leaflet containing a classified list of periodicals or similar publications, a list of commodities of 85 different kinds and their respective non-competing producers, of an attached coupon containing the redemption agreement of a third party of issue.

4. Means for co-operative advertising and 90 means for ascertaining the results therefrom, comprising a leaflet containing a premium list of periodicals; a purchasing list of producers and a coupon, each producer in the list being provided with an identification 95 number and each coupon being provided with the number of the producer with whose goods it is inclosed and with an individual checking number by which it can be traced.

5. Means for co-operative advertising comprising a leaflet having thereon a list of commodities and their respective producers, a list of periodicals and a coupon containing a notice that it is redeemable in payment for subscriptions to the periodicals comprised in the 105 list, said coupon containing means for identifying the producer with whose goods it was inclosed. 100

6. Means for co-operative advertising consisting of a coupon leaflet comprising a list of commodities and their respective producers, a list of periodicals, an attached coupon and identification numbers upon the list of producers and coupon providing means for identifying the producer with whose goods it was 115 inclosed when the said coupon has been detached. 110

7. The hereinbefore described means for co-operative advertising comprising in a leaflet a coupon, a list of publications, a list of commodities and their respective producers, a notice that the coupons are found only in the commodities named, a notice that the coupon is redeemable in payment for subscriptions to the periodicals named, and numbers and letters for checking and identification, 125 substantially as set forth. 120

8. Means for co-operative advertising consisting of a leaflet, comprising a list of commodities and their respective producers, a list 130

- of periodicals, and a coupon, said coupon containing a statement that it will be redeemed in payment for subscriptions to the periodicals named in the list, an identification number corresponding to the list number of the producer with whose goods it is inclosed, and a checking number constituting means for tracing the package within which it was inclosed.
- 1c 9. Means for co-operative advertising consisting of a leaflet comprising a list of periodicals and the number of coupons needed to purchase a subscription to each, a list of commodities and their respective producers, an identification number opposite the name of

each producer and a coupon containing a statement of its cash value, a statement that it is redeemable in payment for subscriptions for the periodicals comprised in the list, the name and address of the redeeming agent, an identification number corresponding to that of the producer with whose goods it is inclosed, and a checking number constituting means for tracing the package from which the coupon was obtained.
